UNITED STATES PATENT OFFICE.

ABNER E. FOSTER, JR., OF COVINGTON, KENTUCKY.

SHOCK-ABSORBER.

1,161,300.

Specification of Letters Patent. Patented Nov. 23, 1915.

Application filed November 10, 1914. Serial No. 871,356.

To all whom it may concern:

Be it known that I, ABNER E. FOSTER, Jr., citizen of the United States, residing at Covington, in the county of Kenton and State of Kentucky, have invented certain new and useful Improvements in Shock-Ab-sorbers, of which the following is a specification.

My invention relates to new and useful improvements in vehicle springs, and has particular reference to the improved construction of springs of the type employed in connection with automobiles.

The principal object of my invention is to combine in a single device a pair of springs which will act not only to take the place of ordinary supporting springs, but will also perform the offices of a shock absorber.

A more specific object of my present invention is to provide a combined supporting and shock absorbing vehicle spring which consists essentially in a body yoke, a pair of oppositely arranged semi-elliptical springs, and a pair of levers which are pivoted intermediate their length in the yoke and are terminally connected to the vehicle chassis, being arranged to bear with uniformity against the terminals of the springs when the vehicle body is either moving toward or away from the axle.

Another and more general object of my invention is to design the spring with such regard to proportion, number and arrangement of parts that it will embody the essential features of simplicity, durability and efficiency, and will be capable of being manufactured at a relatively low cost, as well as being adapted for application to any standard form of automobile.

The above and other incidental objects of a similar nature, which will be hereinafter more specifically treated, are accomplished by such means as are illustrated in the accompanying drawings, described in the following specification, and then more particularly pointed out in the claims, which are appended hereto and form part of this application.

Referring now to the drawings, wherein there has been illustrated the preferred embodiment of this invention as it is reduced to practice, and throughout the several views of which similar reference characters designate corresponding parts, Figure 1 is a side elevation of the rear portion of an auto-

mobile, showing my improved spring in operative assembled relation to the rear terminal of the chassis and the vehicle axle; Fig. 2 is a detail perspective view of the spring; Fig. 3 is a side elevation of the device, illustrating the springs in the positions which they assume when the vehicle wheel is subjected to an impact and moves upwardly toward the vehicle chassis; Fig. 4 is a side elevation, illustrating the manner in which the springs bear against the levers when they (the springs) are re-acting and are returning to normal position; Fig. 5 is a section on the line 5—5 of Fig. 3; and Fig. 6 is a section on the line 6—6 of Fig. 1.

In the embodiment of my invention illustrated in the accompanying drawings, the combined supporting spring and shock absorber includes as its essential features of construction a body yoke A, a pair of levers B and C, and a pair of oppositely disposed semi-elliptical springs D and E. The body yoke A is preferably formed from strap metal, and is substantially rectangular in shape, including as it does two relatively long, parallel vertical members 10 and 11, and upper and lower horizontal members 12 and 13. The members 10 and 11 and 12 and 13 may be formed integrally, if desired, or may be welded, riveted or otherwise properly secured to each other in any manner which may be found expedient and desirable. The levers B and C are also formed from metal and are relatively wide. These levers are formed of relatively wide bar metal so that they will be able to withstand a maximum strain without being of undue weight. The members B and C are, as shown, pivoted intermediate their length on the pivot bolt or rod 14, which connects the vertical members 10 and 11 of the body yoke A at their approximate central points. The two members B and C are so pivoted that the forward terminal 15 of the outer lever C extends beyond the forward terminal 16 of the inner lever B, while the rear terminal 17 of the member B extends rearwardly of the terminal 18 of the member C. The purpose in thus arranging the two levers B and C is to make possible the attachment of the rear terminal 17 of the inner lever B to the outwardly bent terminal portion 19 of the chassis frame member 20 by a shackle 21, and to further make possible the attachment of the forward terminal 15 of the outer le-

ver C to the chassis frame member 20 at a point intermediate the length thereof by a bracket 22. This bracket 22 is formed from a single length of strap iron which is bent intermediate its length to produce the parallel arms 23 and 24. The arm 23 is secured as by bolts or rivets 25 to the chassis frame member 20, while the arm 24 of the bracket is secured by a pivot bolt or pin 26 to the member C. Spacing washers, indicated at 27, may be interposed between the outer faces of the levers B and C and the members 10 and 11 of the body yoke A and between the adjacent faces of the members B 15 and C in order to properly space the levers from each other and from the sides of the yoke in the manner which will be clearly apparent when reference is had to either Fig. 5 or 6.

20 The spring members D and E are substantially similar in construction and design, each consisting of a number of spring leaves, designated individually by the numeral 28. The leaves of the spring D, are 25 arranged so that the shortest leaf is adjacent the horizontal portion 12 of the body yoke, while the longest leaf is remote therefrom. The leaves of the spring E are similarly arranged with respect to each other, the shortest leaf being disposed in engagement with the horizontal portion 13 of the body yoke, and the longest leaf being disposed remote therefrom. It will thus be seen that the longest leaves of the springs D and E are 30 arranged adjacent each other, and that the springs are in effect oppositely arranged, for the concave face of each of the members D and E opens toward the center of the body yoke.

35 40 The terminal of each of the longest leaves of the two members D and E, which leaves will be hereinafter designated individually by the numerals 29 and 30, are terminally provided with pairs of parallel apertured 45 ears or lugs 31. Between each pair of ear members 31 is journaled on a pin or axle 32 a roller 33. These rollers 33 may be formed of metal or of composition. The rollers are, of course, designed to reduce to 50 the lowest possible point the friction between the terminals of the springs D and E and the edges of the levers B and C. It will now be apparent, upon reference particularly to Figs. 1 and 2, that the springs D and E normally tend by the engagement of 55 their rollers 33 with the upper and lower terminals of the levers B and C to hold these members in parallel relation to each other.

60 In attaching the combined vehicle body supporting spring and shock absorber to an automobile, the forward and rear terminals respectively of the members C and B are attached to the chassis frame member 20 by the attaching bracket 22 and shackle 21. 65 The body yoke A of the device is then prop-

erly secured to the housing 34 of the axle by a U-bolt 35, which member embraces the axle and passes through the lower spring E.

From the foregoing description, and particularly upon reference to Fig. 3, it will be 70 apparent that, if the automobile wheel encounters an obstacle and tends to move upwardly toward the body of the vehicle, the two levers B and C will be swung to move their respective forward and rear terminals 75 upwardly and to move their respective rear and forward terminals downwardly. The terminals 16 and 18 of the respective members B and C will swing upwardly against the tension of the spring D, while the terminals 15 and 17 of the respective members C and B will swing downwardly against the tension of the spring E. Thus the two 80 springs D and E serve at all times to support the body of the automobile on the axle, 85 and also act, when the wheel of the vehicle is subjected to an impact, to resist the movement of the vehicle axle upwardly toward the body. On the re-bound the springs D and E co-act to return the two levers B and 90 C to normal parallel position and offer equal resistance against the opposite terminals of the levers in preventing any undue separation of the axle and the body of the vehicle, 95 as shown in Fig. 4.

It is now to be observed that, whether the vehicle wheel is moving toward the vehicle body or is moving away from the vehicle body, such movement will be efficiently resisted by the engagement of the lever terminals with the springs D and E. It is to be further observed that, whether the vehicle axle is moving toward the body or away from the body, the action of the levers is to straighten the 100 springs E and D in both cases.

105 In reduction to practice, it has been found that the form of this invention illustrated in the drawings, and referred to in the above description as the preferred embodiment, is the most efficient and practical; yet 110 realizing that the conditions concurrent with the adoption of this device will necessarily vary, it is desirable to emphasize the fact that various minor changes in details of construction, proportion and arrangement of parts may be resorted to, when required, without sacrificing any of the advantages of this invention, as defined in the 115 appended claims.

Having thus described the invention, 120 what is claimed as new is:—

1. In a device of the character described, a pair of spring members, and a pair of levers pivoted intermediate their length to a point located between the spring members, the terminals of the levers bearing against the terminals of the spring members.

2. A device of the character described including a yoke member, a pair of substan- 125

tially elliptical springs secured thereto, levers pivoted in the yoke and having their terminals freely engaging the terminals of the springs, and means for freely connecting the opposite terminals of the levers to a vehicle body.

3. The combination with a vehicle, of a spring of the character described including a yoke member adapted to be attached 10 to the vehicle axle, a pair of substantially elliptical springs secured to the yoke, levers pivoted in the yoke and having their terminal portions engaging freely against the terminals of the springs, and means freely 15 connecting a terminal of each lever to the vehicle body.

4. The combination with a vehicle, of a spring of the character described including 20 a substantially rectangular yoke adapted to be rigidly secured to the vehicle axle, a pair of substantially elliptical spring members secured to the yoke at the upper and lower terminals thereof, the spring being oppositely arranged with respect to each other, 25 and a pair of levers pivoted intermediate their length at the approximate center of the yoke and having their terminals bearing freely against the terminals of the springs.

30 5. A device of the character described including a yoke member, a pair of levers pivoted intermediate their length at the approximate center of the yoke, the forward

terminal of one lever extending beyond the forward terminal of the other lever, and the 35 rearward terminal of the second-mentioned lever extending beyond the rear terminal of the first-mentioned lever, spring members secured to the upper and lower terminals of the yoke and having their terminals bearing 40 freely against the terminal portions of the levers, and means for pivotally securing the opposite terminals of the levers to a vehicle body.

6. A device of the character described including a yoke member, a pair of levers pivoted intermediate their length at the approximate center of the yoke, the forward 45 terminal of one lever extending beyond the forward terminal of the other lever, and the 50 rearward terminal of the second-mentioned lever extending beyond the rear terminal of the first-mentioned lever, spring members secured to the upper and lower terminals of the yoke, rollers journaled at each terminal 55 of each spring member, said rollers bearing freely against the terminal portions of the levers, and means for pivotally securing the opposite terminals of the levers to a vehicle body.

60 In testimony whereof I affix my signature in presence of two witnesses.
